US00D573009S

(12) **United States Design Patent**
Nenadic

(10) **Patent No.:** US D573,009 S
(45) **Date of Patent:** ** Jul. 15, 2008

(54) **PORTION OF A CARABINER**

(75) Inventor: **John Nenadic**, Camas, WA (US)

(73) Assignee: **Leatherman Tool Group, Inc.**,
Portland, OR (US)

(**) Term: **14 Years**

(21) Appl. No.: **29/275,946**

(22) Filed: **Jan. 10, 2007**

(51) **LOC (8) Cl.** 08-08

(52) **U.S. Cl.** D8/356

(58) **Field of Classification Search** D8/105,
D8/107, 333, 349, 354, 356, 358, 360, 360.1,

(57) **CLAIM**

The ornamental design for a portion of a carabiner, as shown and described.

DESCRIPTION

FIG. 1 is a perspective view of a portion of a carabiner according to my new design;

FIG. 2 is a front elevation view thereof;

FIG. 3 is a rear elevation view thereof;

FIG. 4 is a right side elevation view thereof;

FIG. 5 is a top plan view thereof;

FIG. 6 is a left side elevation view thereof;

FIG. 7 is a bottom plan view thereof; and,

FIG. 8 is a perspective view of the portion of a carabiner shown in the environment of a broken line folding multipurpose hand tool.

The broken lines shown herein are for illustrative purposes only and form no part of the claimed design.

1 Claim, 8 Drawing Sheets
